ROTARY DISPLAYER FOR PAPERBACK BOOKS

Harold L. Hudson, Gregory G. Mt. Pleasant, and Robert K. Scherzer, Liverpool, N.Y., assignors to Gaylord Bros., Inc., Syracuse, N.Y.

Filed Feb. 20, 1973, Ser. No. 333,548

Term of patent 14 years

Int. Cl. D6—04

U.S. Cl. D6—24

FIG. 1.

FIG. 2.

FIG. 3.

FIG. 5.

FIG. 1 is a perspective view of a rotary displayer for paperback books showing our new design;

FIG. 2 is a side elevational view of the display with a portion broken away for convenience of illustration;

FIG. 3 is a top plan view of the display of FIGS. 1 and 2;

FIG. 4 is a bottom plan view on a somewhat reduced scale; and

FIG. 5 is a cross sectional view as taken on the line 5—5 of FIG. 2 through one of the rotary towers.

We claim:

The ornamental design for a rotary displayer for paperback books, substantially as shown and described.
